Luther Bradley
Sethers Patent

The Schedule is as follows in the Sethers Patent and making part of the same containing a description in the words of the said Luther Bradley himself of his improvement in the manufacture of Scythes.

The invention of this improvement in the manufacturing of scythes being a machine to turn the back of the scythe and to crook it in a curvilinear form at one operation of the machine and at one trial consists in constructing and combining the following parts and principles of machinery here described. viz a platform of hard timber is made of suitable height. its top surface is horizontal & its shape is circular forming a part of a circle or a whole circle as may be wanted. Through the center of this horizontal circular platform is laid a large perpendicular shaft upright which turns round from left to right. A little above the surface of the platform two strong arms of hard timber are put through the shaft at right angles with each other and extend horizontally from the shaft about four feet, being well braced with each other and with timber from other arms second foot above, put through the perpendicular shaft similar to the lower arms and for the purpose of securing and supporting said lower arms. To the outside of one of said lower arms and in the same direction with it, is fixed upon the quid a large conical cast iron roller weighing about eight hundred, turned perfectly true being about four feet long, and its diameter at its large end is twelve inches and its small end about four inches. This conical roller must be hung by its quid, under and horizontal arms of said perpendicular shaft pointing with its small end to the centre of the shaft so that the under surface of said roller may fit the horizontal surface of said platform on which it rolls round as said shaft turns. The conical shape of this roller must be such that it may roll equally alike at both of its ends. And the large end describing a circle as much larger than the small end, as twice the length of the said conical roller. The proportion between the diameters of the two ends of this conical roller, may be easily found by knowing the diameters of the coules those two ends describe on said horizontal platform. Upon said horizontal platform (which may be a complete circle, or any convenient portion of it round said perpendicular shaft) and even with the surface of said platform are placed one or more curvilinear gripping jaws, curving a little to the right and pointing to the centre of said perpendicular shaft or more by so. The jaws of this curvilinear gripping jaws are made of large bars of iron faced with steel & tempered. The curvature of the jaws is the same as the scythe and their thickness is equal to the width of the back of the scythe to be turned up. The right hand jaw is permanently held to the platform by a bolt through its center and is forced up to the other jaw horizontally so as to

Chas. T. D. 1837

grip the back of the sayth plate firmly by a strong iron latch. The latch is about fifteen inches long & has a strong and very powerful spring fixed to a gudgeon so that if for any cause be a little thicker than common, this spring will yield and allow the latch to be drawn down to its place. The end of this latch extending to the right has on its outer part a curved angle which acts against the outer end of the said moving jaw, so that when said latch is descended down by the approach of said outer said moving jaw is closed or forced up to the upper jaw and, upon the back of the sayth plate which is now perpendicular viz edge upward as gripped in said moving jaw, and involuntarily tends down all the time the sayth plate and rolls on over it compressing it firmly upon the surface of the permanent jaw of said iron. The length of which jaw must be such as to leave the point of the sayth without turning up a back. As soon as the roller presses over the edge of the plate, a spring fixed to the outer end of said moving jaw opens it and the workman then takes the sayth plate out, which is then to be finished with the hammer in the usual manner. It is best to have a proper furnace in which to heat a large number of sayth plates at one time to an moderate red heat, and to preserve this degree of heat while the machine is in operation. It is also contemplated to make the roller a perfect cylinder. Viz. The diameter of its ends the same, and to have it placed on the common calculated arms of a wheel whose shaft or arms lies horizontally over the iron platform, so that said roller will be moved over the platform to the right and produce the same effect by the rolling of said wheel. This mode of giving motion to a roller to produce the effect required of this machine will answer very well for a small factory. Another mode of putting in motion said roller last mentioned is by having it hung by its gudgeon in a perpendicular frame formed by two timbers about fifteen feet long, & so arranged at their upper ends as is to allow the roller to be rolled back & forth on the said frame and when it comes to the edge of the plate in said iron gripping vice, said frame will then give a proper degree of pressure to the roller. This vibratory motion of the frame to roll the roller forward and back again may be obtained by an horizontal arm connected to this roller furnace and ~~extending~~ to the shaft of the common water wheel, by which the proper motion may be given to said horizontal arm, by two cows, or eccentricities on said water wheel shaft, one of which cows will roll the roller forward over the gripping vice and the other will roll it back involuntarily, where it will stop a short time and admit the sayth plate to be put under said gripping vice which is the same in all these different ways contemplated to be put in operation. The platform in these two last modes of giving motion to the said roller will be very simple and admit of but one gripping vice. This cylindrical cast iron roller for this

to fasten it and fitting it to the platform referred to above and in this manner
the use of this machine saves much time in making a saw. It is to be noted that the
moving jaw of the gripping vice has two or more of these iron bolts on the under side
and let into the platform. as well as the permanent jaw as back side of said moving
jaw. it is to prevent said moving jaw from rising up or from being bent up above the hori-
zontal surface of the platform. and when the side plate is put into said gripping vice edges
upwards its back side upon said side plate as the as the edge of the back of the back of the
side which must be straight when put into said vice unless it back turned. The forma-
lne jaw of the gripping vice must be no longer than the back of the saw blade that is to be
turned. and for sides of different length it is best to have permanent jaws also of different
lengths accordingly to be put in and taken out. & all to fit the said moving jaw especially
in machines that have but one gripping vice.
